FLUID FUEL BURNER CONTROL SYSTEM

Thomas J. Davidson, Los Angeles, Calif., assignor to Robertshaw-Fulton Controls Company, Greensburg, Pa., a corporation of Delaware

Application January 26, 1954, Serial No. 406,147

7 Claims. (Cl. 158—135)

This invention relates to fluid fuel burner control systems and more particularly to gas burner control systems which include a main burner, a pilot burner, a main valve, and a safety valve, as well as means responsive to a flame at the pilot burner for so controlling the operation of the safety valve as to prevent passage of gas to the main burner unless a flame is present at the pilot burner.

A system of this character finds particular utility in the control of the burner of a heating appliance such as a gas range which includes a main manually operable or remotely controlled valve. Upon opening of the main valve, gas is supplied only to the pilot burner where it is ignited by suitable means such as an electrically heated catalytic igniter. Following ignition of the pilot burner and after an interval sufficient for heating of the flame sensitive element of the safety valve by the pilot flame, the safety valve opens automatically to permit flow of gas to the main burner where it is ignited by the pilot burner. When, to discontinue the heating operation, the main valve is closed, flow of fuel to both the main and pilot burners is terminated so that the foregoing procedure must be repeated to re-establish flame at the main burner.

The flame sensing element of the safety valve may comprise an expansible bellows for actuating the valve with a bulb positioned adjacent the pilot burner and communicating with the bellows through a capillary tube, the bulb containing a suitable thermal fluid which will expand upon heating to expand the bellows and open the valve. Since heating of the bulb after the pilot flame is established and cooling of the bulb after the pilot flame is extinguished will require a certain amount of time for heat transfer, there is a delay period subsequent to the closing of the main valve and resultant termination of fuel flow to the pilot burner during which period the bulb is still warm and the safety valve remains open.

If, during such delay period, the main valve is reopened, fuel will flow to both the main and pilot burners so that it accumulates in the oven and an explosion may occur when the pilot burner is relighted by the ignition means.

To eliminate the danger pointed out above, it is an object of this invention to sustain a flame at the pilot burner during such delay period, the flame being made small enough to be ineffective to heat the flame sensing element but being available to effect reignition of the main burner in the event of reopening of the main valve.

Another object of the invention is to supply fuel to the pilot burner at a relatively high initial rate to facilitate ignition and assure rapid heating of the thermal sensing element upon opening of the main valve with subsequent reduction of the fuel flow to an intermediate rate sufficient to maintain the required normal operating temperature of the thermal sensing element.

In a preferred embodiment of the invention, the above objects are accomplished through the provision of a plurality of conduits communicating with a source of fuel and adapted to be selectively connected to the pilot burner,

2

at least one of the conduits supplying a limited amount of fuel and remaining in communication with the pilot burner as long as the main burner safety valve remains open.

Other objects and advantages will appear from the following specification taken in connection with the accompanying drawing which is a schematic view of a control system for a fuel burner embodying this invention, a portion thereof being shown in section.

Referring to the drawing, the control system is shown as associated with a main burner 10 which receives fuel from a supply manifold 12, flow of fuel from the manifold 12 to the main burner 10 being under the control of two valve means: a first thermally responsive valve means 14, and main valve means 16 here shown as manually operable but which may be remotely controlled if desired.

Ignition means, here shown as an electrically heated catalytic igniter 20, is disposed in igniting relation with the pilot burner 22 which is in turn disposed in igniting relation with the main burner 10. The pilot burner 22 is supplied with fuel through a pilot supply conduit 24 connected therewith, flow of fuel in the conduit 24 being controlled by a plurality of means to be more fully described hereinafter.

A casing 26 contains the thermally responsive valve means 14 which may comprise a valve chamber 28 formed in the casing 26 and provided with an inlet opening 30 and an outlet opening 32. The outlet opening 32 communicates with a main supply conduit 34 connected to the main burner 10. Disposed in the valve chamber 28 is a valve seat 36 cooperable with a first valve member 38 to interrupt flow between the inlet 30 and the outlet 32. A coil spring 40 acts between a wall 42 of the valve chamber 28 and the valve member 38 to bias the valve member 38 into engagement with the valve seat 36.

Depending from the lower side of the valve member 38 is a valve stem 44 which extends slidably through a bore 46 in the casing 26. The free end 48 of the valve stem 44 extends beneath the casing 26 to abut a lever 50 which is pivoted at one end 52 in a bracket 54 secured to the casing 26.

The lever 50 is adapted to be moved about its pivot by a thermally responsive device which may comprise an expansible element 56 communicating with a bulb 58 through a capillary tube 60. The bulb 58 contains a suitable thermal fluid which, when heated, will increase the pressure within the expansible element 56 to expand the same. The bulb 58 is disposed adjacent the pilot burner 22 to be heated by a flame emanating therefrom.

The expansible element 56 is mounted on a cover 62 secured to the lower side of the casing 26 and movement is transmitted from the expansible element 56 to the lever 50 by means of a thrust button 64 carried on the upper surface of the expansible element and abutting the lever 50. It will be apparent that in the absence of a flame at the pilot burner 22, the expansible element 56 will be in its contracted condition and the spring 40 will hold the valve member 38 against the valve seat 36. It will also be apparent that a flame emanating from the pilot burner 22 will be effective to heat the bulb 58 causing expansion of the expansible element 56, counterclockwise rotation of the lever 50 and movement of the valve member 38 against the bias of the spring 40 to establish communication between the inlet 30 and outlet 32 of the valve means 14. However, after the pilot flame is extinguished, a period of time must necessarily elapse before the bulb 58 cools sufficiently to cause contraction of the expansible element 56 and permit return movement of the valve member 38 into engagement with the valve seat 36.

Fuel is supplied to the inlet 30 of the valve means 14 through a first conduit 66 which is connected to the

manually operable valve means 16. The manually operable valve means 16 may comprise a simple gas cock (not shown) adapted to receive fuel from the manifold 12 through a suitable connection 68.

The outlet of the manually operable valve means 16 is also connected to the pilot burner conduit 24 through a connection 70 and a cross 72. Flow control means, such as a needle valve 74, is interposed in the connection 70 to limit fuel flow from the manually operable valve means 16 to the cross 72. The manually operable valve means 16 thus controls the flow of fuel to both the thermally responsive valve means 14 and the pilot burner 22.

Fuel will be supplied to the pilot burner 22 through the connection 70, cross 72 and conduit 24 as long as the manually operable valve means 16 is open. However, it is desirable to maintain a supply of fuel to the pilot burner 22 as long as the thermally responsive valve means 14 is open regardless of the condition of the manually operable valve means 16. To this end, a second conduit 76 is provided to supply stand-by fuel directly from the manifold 12 to the cross 72 under the control of second thermally responsive valve means 80.

The valve means 80 may comprise a valve chamber 82 formed in the casing 26 and provided with an inlet 84 and outlet 86. The inlet 84 communicates with a bypass conduit 78 which is connected to the manifold 12 and the outlet 86 communicates with the second conduit 76 which is connected to the cross 72. A valve seat 88 disposed in the valve chamber 82 is cooperable with a second valve member 90 to interrupt flow between the inlet 84 and outlet 86.

A spring 92 acting between the casing 26 and the valve member 90 serves to bias the valve member 90 toward the valve seat 88 and a valve stem 94 extends between the valve member 90 and the lever 50 of the thermally responsive actuating device. It will be apparent that rotation of the lever 50 under the influence of a flame at the pilot burner 22 will cause an upward movement of the valve stem 94 to move the valve member 90 away from the valve seat 88. When the valve member 90 is not so moved, it will be held against the valve seat 88 by the spring 92 to prevent fuel flow between the inlet 84 and the outlet 86.

Flow control means, here shown as a needle valve 96, is disposed in the conduit 78 to limit fuel flow therein.

In apparatus of this type, ignition of the pilot burner fuel is facilitated if the pilot burner is supplied with a high rate of fuel flow prior to ignition thereof. Such rate exceeds that required for steady state operation so that the rate of fuel flow to the pilot burner is preferably reduced subsequent to ignition of the pilot flame. Accordingly, means is provided for supplying additional fuel to the pilot burner prior to ignition and comprises a third conduit 98 and a fourth conduit 100 connected to the conduit 66 and to the cross 72 respectively and communicating with each other through third thermally responsive valve means 102.

The thermally responsive valve means 102 comprises a valve chamber 104 formed in the casing 26 and provided with an inlet 106 and an outlet 108. The inlet 106 communicates with the conduit 98 and the outlet 108 communicates with the conduit 100. A valve seat 110 disposed in the valve chamber 104 is cooperable with a third valve member 112 to interrupt fuel flow between the inlet 106 and outlet 108.

A spring 114, acting between the valve seat 110 and the valve member 112 acts to bias the valve member 112 away from the valve seat 110 and a valve stem 116 extends between the valve member 112 and the lever 50 of the thermally responsive actuating device. It will be apparent that rotation of the lever 50 under the influence of a flame at the pilot burner 22 will cause upward movement of the valve stem 116 and associated valve member 112 to move the valve member 112 into engagement with

the valve seat 110 and prevent fuel flow between the inlet 106 and the outlet 108. When the valve member 112 is not so moved, it will be held away from the valve seat 110 by the spring 114 to permit fuel flow.

5 Flow control means is provided for limiting fuel flow in the conduit 100 and is here shown as comprising a needle valve 118 disposed therein.

It will be apparent that the cross 72 connects a plurality of conduits with the conduit 24 and pilot burner 22 and the various valves hereinbefore described act to selectively establish communication between such conduits and the manifold 12 to thereby control the rate of fuel flow to the pilot burner 22. The coaction between these valves and conduits will be brought out more fully 15 in the description of the operation of the system which follows.

Assuming that the apparatus is in the condition shown in the drawing with no flame existing at any of the burners and it is desired to place the burner 10 in operation, 20 the manually operable valve means 16 is moved to open position to permit fuel to flow through conduit 66 to the first thermally responsive valve means 14 and to the pilot burner 22 through the needle valve 74, connection 70, cross 72 and conduit 24. Fuel will also flow from the 25 conduit 66 through conduit 98, third thermally responsive valve means 102, conduit 100, needle valve 118 and cross 72 to conduit 24 and the pilot burner 22. Thus the rate of fuel flow to the pilot burner 22 will be equal to the total amount of fuel which can be passed through 30 the needle valves 74 and 118.

Fuel flowing from the pilot burner 22 will impinge upon the igniter 20 to cause ignition and establish a flame at the pilot burner 22. The needle valve 118 is preferably set to permit a relatively high fuel flow rate to assure easy ignition and establish an initial flame at the pilot burner of substantial size which will heat the bulb 58 as rapidly as possible.

When the bulb 58 is heated, the thermal fluid contained therein will expand to cause expansion of the 40 expandible element 56 with consequent counterclockwise movement of the lever 50. As the lever 50 is moved about its pivot, the valve members 38, 90 will be moved away from their respective seats and the valve member 112 will be moved into engagement with its seat.

Movement of the first valve member 38 away from its seat will establish communication between the inlet 30 and outlet 32 of the valve means 14 to supply fuel to the main burner 10 through the conduit 34. Fuel flowing from the main burner 10 will be ignited by the flame at 50 the pilot burner 22.

Movement of the valve member 90 away from its seat will establish communication between the inlet 84 and outlet 86 of the valve means 80 and will permit fuel to flow through the second conduit 76 to the cross 72 thence 55 to the pilot burner 22 through the conduit 24.

Movement of the valve member 112 into engagement with its seat will terminate fuel flow to the conduit 100. Thus, in the heated condition of the bulb 58 and open position of the valve means 16, fuel is supplied to the 60 pilot burner 22 through the connection 70 and second conduit 76 which communicate with the pilot burner 22 through the conduit 24 and cross 72. Accordingly, under such conditions, the rate of fuel flow to the pilot burner 22 is the sum of the fuel rates which are passed by the needle valves 74 and 96. The needle valve 96 is preferably set to pass a volume of gas somewhat less than that passed by the needle valve 118 so that the pilot burner will be supplied with fuel at an intermediate rate in the heated condition of the bulb 58, such rate being sufficient to provide a flame large enough to assure maintenance of the heated condition of the bulb 58 as well as ignition of fuel flowing from the main burner 10.

In the event the manually operable valve means 16 is closed while the apparatus is in steady state operating 75 condition and then is reopened before the bulb 58 has

had a chance to cool, the flow of fuel to the pilot burner will be decreased but will not be completely terminated. When the manually operable valve means 16 is closed, fuel is prevented from flowing to the conduit 66 and connection 70 so that no fuel can be supplied to the main burner 10 or to the cross 72 through the valve 16. However, fuel will be continued to be supplied to the pilot burner 22 through the bypass conduit 78, valve means 80, conduit 76, cross 72 and conduit 24. The rate of such pilot fuel flow will be determined by the needle valve 96 and is preferably small enough to prevent heating of the bulb 58 so that the same may cool but which is sufficient to assure the maintenance of a flame at the pilot burner and thus assure immediate ignition of the main burner 10 upon reopening of the manually operable valve 16.

In the event the manually operable valve 16 is closed and is not reopened, the bulb 58 continues to cool until the thermal fluid therein contracts to cause contraction of the expansible element 56 and clockwise movement of the lever 50. Such movement of the lever 50 permits movement of the valve members 38, 90 under their respective biases into engagement with their seats and movement of the valve member 112 away from its seat so that the apparatus is restored to its initial condition as shown in the drawing. It is to be noted that when the various parts of the apparatus are so returned to their initial positions, flow of all fuel to the pilot burner 22 is prevented and the flame at the same is extinguished.

It will be apparent from the foregoing that the herein disclosed apparatus provides a control system for fluid fuel burners wherein a single pilot burner may be provided with a number of different rates of fuel flow to produce an exceptionally fast acting and safe control and that it accordingly accomplishes the objects of the invention.

Although a specific embodiment of the invention has been shown and described, it will be apparent that many modifications may be made by those skilled in the art. Such modifications may be made in the details of construction and arrangement of parts without departing from the scope of the invention as set forth in the appended claims.

It is claimed and desired to secure by Letters Patent:

1. In a control and ignition system for a main fuel burner having a source of fuel supply, comprising a single pilot burner for igniting the main burner, a first valve means operable for controlling fuel flow to the main burner and being biased to a flow preventing position, a second valve means operable for controlling fuel flow to said pilot burner and being biased to a flow preventing position, a third valve means operable for controlling fuel flow to said pilot burner and being biased to a flow supplying position, thermally responsive means located to be heated by said pilot burner, main valve means operable for controlling fuel flow to said main burner through said first valve means and to said pilot burner through said third valve means, a pilot supply conduit and a connection from said main valve means direct to said pilot burner for augmenting the fuel flow thereto from said third valve means when said thermally responsive means is heated below a predetermined temperature, flow control means in said connection, means operatively associated with said thermally responsive means for operating said first and second valve means to flow supplying position and said third valve means to flow preventing position when said thermally responsive means is heated to said predetermined temperature, said pilot burner thereby being supplied with fuel through said second valve means and said pilot supply conduit, and flow control means cooperable with said second valve means and cooperable with said flow control means in said connection for reducing said fuel supply to the pilot burner but in an amount sufficient to maintain heating

of said thermally responsive means to said predetermined temperature.

2. In a control and ignition system as claimed in claim 1 wherein a bypass conduit is provided for said second valve means around said main valve means for supplying fuel to said pilot burner independently of said main valve means while said thermally responsive means remains heated to said predetermined temperature, said flow control means cooperable with said second valve means being positioned for controlling the fuel supply in said bypass conduit whereby the heat of said pilot burner is insufficient to maintain said predetermined temperature when said main valve means remains in a flow preventing position for a predetermined period.
3. In a control and ignition system for a main fuel burner having a source of fuel supply, comprising a single pilot burner for igniting the main burner, a first valve means having inlet and outlet openings and a first valve member biased for preventing flow through said openings, 20 a main supply conduit connecting said outlet of said first valve means to the main burner, a first conduit connecting said inlet of said first valve means to the source, a second valve means having inlet and outlet openings and a second valve member biased for preventing flow through said openings, a bypass conduit connecting said inlet of said second valve means to the source, a pilot supply conduit connected to said pilot burner, a second conduit connecting said outlet of said second valve means to said second valve member, a third valve means having inlet and outlet openings and a third valve member biased for supplying fuel through said openings, a third conduit connecting said inlet of said third valve means to said first conduit, a fourth conduit connecting said outlet of said third valve means to said pilot supply conduit, thermally responsive means located to be heated by said pilot burner, and means operatively associated with said thermally responsive means for operating said first and second valve members to flow supplying position and said third valve member to flow preventing position when said thermally responsive means is heated to a predetermined temperature.

4. In a control and ignition system for a main fuel burner having a source of fuel supply, comprising a single pilot burner for igniting the main burner, a first valve means having inlet and outlet openings and a first valve member biased for preventing flow through said openings, 45 a main supply conduit connecting said outlet of said first valve means to the main burner, a first conduit connecting said inlet of said first valve means to the source, a second valve means having inlet and outlet openings and a second valve member biased for preventing flow through said openings, a bypass conduit connecting said inlet of said second valve means to the source, a pilot supply conduit connected to said pilot burner, a second conduit connecting said outlet of said second valve means to said pilot supply conduit, a third valve means having inlet and outlet openings and a third valve member biased for supplying fuel through said openings, a third conduit connecting said inlet of said third valve means to said first conduit, 50 a fourth conduit connecting said outlet of said third valve means to said pilot supply conduit, thermally responsive means located to be heated by said pilot burner, main valve means operable for controlling fuel flow to said main burner through said first conduit and to said pilot burner through said third conduit, said pilot supply conduit being connected from said main valve means direct to said pilot burner for augmenting the fuel flow thereto from said fourth conduit when said thermally responsive means is heated below a predetermined temperature, and means operatively associated with 55 said thermally responsive means for operating said first and second valve members to flow supplying position and said third valve member to flow preventing position when said thermally responsive means is heated to a predetermined temperature.

5. In a control and ignition system as claimed in claim 4 wherein flow control means are cooperable with said second valve means for reducing said fuel supply to the pilot burner but in an amount sufficient to maintain heating of said thermally responsive means to said predetermined temperature.

6. In a control and ignition system as claimed in claim 5 wherein separate flow control means are located for controlling flow from said third valve means and said main valve means respectively to said pilot burner, said flow control means for said main valve means being adapted for maximum fuel flow to establish a high initial flame at said pilot burner. 10

7. In a control and ignition system as claimed in claim 6 wherein said flow control means cooperable with said second valve means is adapted for lesser fuel flow than that of said flow control means for said main valve means but being sufficient to maintain said flame and said predetermined temperature of said thermally responsive means.
